UNITED STATES PATENT OFFICE.

JOHN F. CURTIS, OF CHICAGO, ILLINOIS, ASSIGNOR TO O. F. JORDAN COMPANY, OF EAST CHICAGO, INDIANA, A CORPORATION OF INDIANA.

RAILROAD SPREADER.

Application filed April 18, 1925. Serial No. 24,140.

To all whom it may concern:

Be it known that I, JOHN F. CURTIS, a citizen of the United States, and a resident of Chicago, county of Cook, and State of Illinois, have invented certain new and useful Improvements in Railroad Spreaders, of which the following is a specification.

This invention relates to improvements in railroad spreaders and consists of the matters 10 hereinafter described and more particularly pointed out in the appended claims.

In railroad spreaders embodying a car having side or main spreader wings and bank shaping or extension wings, the side 15 wings are so pivotally connected to the car as to be capable of a vertical adjustment as well as a horizontal swinging movement toward and away from the car. The extension wing is so connected to the main 20 spreader wing as to be used either as material carrying wing or a bank shaping wing. When used as a material carrying wing, it is swung about its pivotal connection with the main spreader wing so as to extend substantially 25 parallel with the car and its free end is connected by a removable brace with the side of the car. When said extension wing is used as a bank shaping wing, it is arranged parallel with the main spreader 30 wing as an extension thereof. However, it is sometimes desired to use the main spreader wing alone. Under such conditions the extension wing is swung about its horizontal axis so as to be inoperative.

With the extension wing being used as a bank shaper, it is apparent that great strains are imposed upon both wings due to the resistance of the material being operated upon, and folding and telescopic brace bars 40 are employed between the rear sides of both wings and the car body. The connection between said braces and car body is provided by a shaft to which the inner ends of the brace bars are connected. When it 45 is desired to change the angular relation between said wings and car, this may be brought about by the telescopic features of the brace bars but when it is desired to swing the wings back against and parallel with the car for the purpose of transport from place to place, the shaft is rotated to fold up the brace bars. Again, some times it 50 is necessary to use only the main spreader wing and under such conditions the exten-

sion wing is swung vertically about its horizontal axial connection with the main wing so that it is out of the way. Under such conditions, as well as when the extension wing is used as a carrying wing the brace bars associated with the extension wing are disconnected therefrom and are folded back toward and secured to the car, thus leaving the braces associated with the main spreader wing undisturbed as far as their connection with the main spreader wing and operating shaft is concerned.

One of the objects of the present invention is to provide a construction, wherein the brace bars associated with the extension wing may be folded back against the car 70 without in any manner interfering with the operation of the braces of the main wing.

A further object of the invention is to provide a novel operating shaft for the brace bars by means of which one set of brace bars 75 may be quickly released from the operating influence of said shaft when necessary.

Still another object of the invention is to provide a sectional shaft for the said brace bars, wherein one shaft section may be 80 readily disconnected from the other so that said first section is rendered inoperative without disturbing the operative relation of the other.

These objects of the invention as well as 85 the many advantages thereof will more fully appear as I proceed with my specification.

In the drawings:

Fig. 1 is a top plan view of a railroad 90 spreader embodying my invention.

Fig. 2 is a view in side elevation thereof.

Fig. 3 is a detail sectional view on an enlarged scale through the brace bar operating shaft, as taken on the line 3—3 of Fig. 2.

Fig. 4 is a longitudinal sectional view through one form of shaft coupling embodying my invention, the plane of the section being indicated by the line 4—4 of Fig. 3.

Referring now in detail to that embodiment of the invention illustrated in the accompanying drawings: 1 indicates a car resembling an ordinary railroad flat car but of a narrow width so that the spreader 105 wings may work close to the rails. As shown herein, said car comprises an under frame 2 mounted upon suitable front and rear trucks

- 3—4 and upon said under frame is laid the floor or deck 5 extending from end to end of the car. At a point slightly to the rear of the front truck, are provided upright columns 5 6—6, one at each side of the car, which are suitably secured to the under frame and extend nearly to the rails, said columns being braced at their top to said car in a manner well known. Vertically movable 10 in said columns are posts 7—7 operated by suitable air engines 8—8 arranged on the deck near said columns, said engines receiving their source of pressure fluid from a tank 9 arranged on said deck about midway between its ends.

The two sides of the car are exactly alike except that the parts occupy reversed positions and, therefore, a description of the parts on one side of the car will suffice for 20 both. However, it should be here stated that the wings are independently operated and that either one or both of them may be used at one time according to the work to be done.

- 25 On each post 7 at the bottom end thereof is a heavy hinge plate 10 and to this is secured a heavy hinge section 11 of the main or side spreader wing 12. The hinge plate and hinge section are connected together by a 30 vertical axis pin 13 and the main or side spreading wing 12 is secured to the hinge section 11 by a horizontally disposed pin 14. The two hinge pins being arranged at a right angle allow the wing to be swung in both a vertical and a horizontal plane. The 35 horizontal movement occurs in the distending or retracting of the wing away from and toward the car and the vertical movement of the wing occurs when it is desired to incline the same with relation to a horizontal plane for the purpose well known. The free or outer end of the wing 12 is sustained and braced by a brace 15 which is shown with its central portion broken away 40 in Fig. 1. The said brace is telescopic and its bottom end is pivotally connected to said wing 12 while its top end is vertically pivoted to a plate 16 carried by the post 7. As the wing 12 is connected to the post 7 45 as before described, it is apparent that it will rise and fall therewith under the operation of the engine 8. In Fig. 1, one wing 12 is shown distended while the other wing is shown as folded back against the car for 50 transport purposes.

In connection with the side spreader wing there is employed a secondary wing 17 which is operatively connected to the outer end of said side spreader wing by means of a hinge plate construction 18 which permits movement of said wing 17 about both a vertical and a horizontal axis so that said secondary wing may be swung into either a position parallel with said side spreader wing to form an extension or bank shaping

wing as shown in full line in Fig. 1, or into a position parallel with the car to form a material carrying wing as best shown in dotted lines in said Fig. 1. When in said last mentioned position the free end of said 70 secondary or extension wing may be connected to the side of the car by means of a removable and detachable brace 19, best shown in dotted lines in said Fig. 1.

For holding the side wing and the extension wing distended as shown in full lines in Fig. 1, against the ballast, I employ a plurality of braces 20 and 21 respectively, arranged in pairs with one pair 20 associated with the main or side spreading wing and 75 with the other pair 21 associated with the secondary or extension wing. Instead of making said braces in the form of rigid struts or beams, I prefer to use the toggle and telescopic form of braces best shown in 80 the Jordan Patent No. 996,256 of June 27, 1911. The braces 20 are permanently attached at their outer ends to brackets 22 on the rear side of the side spreader wing 12 while the outer ends of the braces 21 85 are capable of detachable connections to similar brackets 22^a on normally the rear side of the secondary or extension wing 17. By reason of the telescopic feature of said braces the working scope of the wings as 90 well as its horizontal angular position with respect to the car may be adjusted as desired. The brace bars 20, 21 are substantially alike but are of different lengths as 95 best shown in Fig. 1 and each comprises 100 inner and outer sections 20^a—20^b and 21^a—21^b. The sections comprising each bar are pivotally connected together by a toggle or folding rule joint 23 and several of said sections are made up of a plurality of parts 105 which are telescopic as best shown in Fig. 1 of the drawings. As the specific construction of the folding rule joint and telescopic features of the brace form no particular 110 part of the present invention, they are not described in detail herein.

The inner ends of all the braces, except the shortest one thereof, which is located closest the column 6, extend into and are loosely connected to socketed castings 24—24 and 25 respectively, so as to be capable of a limited amount of movement with respect thereto. The castings 24—24 are non-rotatively mounted on a shaft section 26 which is preferably square in cross section while the casting 25 together with the inner end of the shorter brace bar 20 is likewise mounted on a second shaft section 27 in line with said shaft section 26 and adapted to be connected thereto by a coupling 28 to be described in detail later, so that when desired said sections may be rotated as a non-sectional shaft, or they may be disconnected so that rotative movement may be imparted to one without affecting the other. Both shaft sections are 115 120 125 130

105

1,550,785

3

rotatively mounted in bearing brackets 5^a extending laterally from the car underframe, said brackets being interconnected with the inner ends of the brace bars 20—21 as best shown in Fig. 1.

The coupling 28 is made up of two coupler sections 28^a—28^b secured respectively to the shaft sections 26 and 27 and operatively connected together so that one coupler section 10 may be locked to the other or so that one coupler section may be disconnected from the other for relative rotative movement but not for longitudinal separation. The coupler section 28^a is made up of two identical 15 parts each including longitudinal extending sleeves 29 of angular cross section, and a radial flange portion 30. The sleeves 29—29 are adapted to embrace one half of the squared end of said shaft section 26 and each 20 has a longitudinal bolting flange 31. When a pair of such coupler sections are placed on the end of the shaft section 26, their bolting flanges will substantially meet in the plane of opposite corners of said shaft section and 25 bolts 32 passing through said flanges securely clamp them together and onto said shaft section. In each radial flange portion 30 is provided a longitudinal hole 33, thus providing two of such holes diametrically 30 oppositely disposed in each coupler section.

The coupler section 28^b is substantially the same construction as that just described and the like parts are similarly numbered, the only difference being that the radial flange 35 portions 30—30 of said section 28^b include peripheral portions 30^a—30^b which overhang the peripheral portion of the flanges 30—30 of the other coupler section as best shown in Fig. 4 so as to prevent longitudinal separation between said sections. Bolts 34 are 40 used to rotatively connect said coupler sections together, said bolts passing through the holes 33 in said coupler section flanges and nuts are then threaded onto said bolts. 45 As it is apparent, the shaft sections may be disconnected as far as relative rotation is concerned by removing the bolts 34 without in any manner disturbing their abutting end-wise relation. Secured to that end of the 50 shaft section 27 nearest the shorter brace bar 20 is an arm 35 to which is operatively connected the outer end of a piston rod 36 having a piston head arranged within a transversely disposed engine or cylinder 37 located underneath the car deck. Said cylinder is connected up with the air tank 9 in any suitable manner so that an in and an out power stroke may be imparted to the 55 piston rod to rock the shaft provided by the shaft sections 26 and 27.

Assume that the parts are in the position shown at the top of Fig. 1 wherein the two wing sections are folded back against the car for transport purposes and the brace 60 bars 20 and 21 are folded upwardly as shown

and it is desired to distend said wings into the full line position shown at the bottom of said Fig. 1. The engine 37 would be actuated to thrust its piston outwardly and this will impart a rocking movement to the 70 shaft sections 26, 27 assuming them to be rotatively locked together by the coupling 28. Said shaft sections through the brace bars 20—21 will swing the wings away from the car about their vertical axis upon the 75 post 7 in the column 6, until the sections of the brace bars are aligned and further unfolding movement is prevented by the folding rule joint in said bars. The side wing and extension wing will then be in the operative position shown at the bottom of Fig. 1. Relative vertical angular position of the extension wing with respect to the side wing may be had within certain limits without disturbing the connection between said extension wing and associated brace bar. Assume, however, that it is desired to use the extension wing as a material carrying wing as shown in dotted lines in Fig. 1. The 80 brace bars 21—21 are detached from the 85 brackets 22^a on the said wing 17 and the bolts 34 are removed from the coupler sections, thus permitting the shaft sections 26—27 of being rotated independently of each other. The braces 21—21 may then be folded up in 90 a suitable manner and then temporarily secured to the car in an out of the way position. The extension wing is then swung about its vertical pivotal connection with the side wing into a position parallel with the 95 car as shown in dotted lines in Fig. 1 and its free end is then connected to the car by the brace bar 19 as shown in said figure. The excess of such ballast as is now being operated upon will be carried along by said wings to a point ahead to be disposed of as for instance to fill in a cut or the like.

Should it be found necessary to change the horizontal angular position of the main spreader wing with reference to the car, this may be done by reducing the length of the telescopic braces 20—20. However, should this change be only momentarily as when passing an obstruction, the same may be brought about by rotating the shaft section 100 110 115 120 125 130 27 (the shaft section 26 being disconnected therefrom) to swing the wing 13 inwardly, far enough to pass said obstruction. After the obstruction has been passed, the wing is readily returned to its original position by rotating said shaft section 27 in the opposite direction. Should it thereafter be desired to use the wing 17 as an extension wing, the brace 19 is disconnected and removed and the wing 17 is swung into the full line position shown in Fig. 1. The brace bars 21 are unfolded and again connected to the brackets on the rear side of said wing 17 and the holes 33 in the coupler sections 28^a—28^b are brought into registration and

the bolts 34 repositioned to rotatively secure said shaft sections together. To fold the wings back against the car, the shaft formed by said shaft sections 26—27 is rotated when 5 the braces 20—21 will fold up into the position shown at the top of said Fig. 1.

Under some conditions, it might be advisable to provide secondary braces between the toggle or folding rule joints 23 of the 10 several brace bars 20—21. To this end I provide laterally extending ears 23^a—23^a on parts of said joints as best shown in Figs. 1 and 2, which ears are adapted to detachably receive the ends of secondary brace bars 15 38—38. Said secondary brace bars assist in holding the brace bars 20—21 in proper spaced relations at points between their ends when distended. When the wing 17 is used 20 as a material carrying wing as before described, the intermediate secondary brace bar 38 is detached from its associated ears and removed from the apparatus so that the brace bars 21—21 may be folded into the 25 position shown in Fig. 2.

25 The many advantages of the invention will be apparent to those familiar with the art. The shaft sections may be readily disconnected rotatively when necessary and may be as readily connected together again into 30 exact alignment. The parts are strong and are so constructed as to be applied either in the assembly of a new spreader or may be assembled in spreaders now in use by cutting the shaft at the proper place, applying 35 the parts and bolting them on, because it is not necessary to position them from the end of a shaft and then slide them along said shaft.

40 While in describing my invention, I have referred to certain details of mechanical construction and arrangement of parts, the same is for purpose of illustration only and I do not wish to be limited thereto except as may be pointed out in the appended claims.

45 I claim as my invention:

1. The improvement herein described comprising a car in combination with a side wing pivoted thereto, a secondary wing operatively connected to said side wing, and wing swinging and holding braces adapted for either a simultaneous operation or an independent operation, and means for operating said braces.

50 55 The improvement herein described comprising a car in combination with a side wing pivoted thereto, a secondary wing operatively connected to said side wing, and folding wing swinging and holding braces adapted for either a simultaneous operation or an independent operation, and means for operating said braces.

60 65 The improvement herein described comprising a car in combination with a side wing pivoted thereto, a secondary wing operatively connected to said side wing, wing

swinging and holding braces, and means for operating said braces, said means including disconnectible parts whereby one wing may be swung independently of the other, after the braces associated with said other wing 70 have been detached therefrom.

4. The improvement herein described comprising a car in combination with a side wing pivoted thereto, a secondary wing operatively connected to said side wing and 75 adapted to form an extension thereof, a shaft mounted on said car, and wing swinging and holding braces connecting said shaft and wings, said shaft being so constructed that a part thereof may be rendered inoperative 80 without disturbing the operativeness of the other part thereof.

5. The improvement herein described comprising a car in combination with a side wing pivoted thereto, a secondary wing 85 operatively connected to said side wing and adapted to form an extension thereof, a shaft mounted on said car, means for rocking said shaft, and wing swinging and holding braces connecting said shaft and wings, said 90 shaft being so constructed that one part may be disconnected from the other part to which said means for rocking the shaft is affixed.

6. The improvement herein described comprising a car in combination with a side 95 wing pivoted thereto, a secondary wing operatively connected to said side wing and adapted to form an extension thereof, a shaft mounted on said car, and comprising a plurality of sections adapted to be connected 100 together and to be disconnected from each other, means for rocking said shaft, fixed to one of said sections, and wing swinging and holding braces connecting said side wing to one shaft section and the extension 105 wing to the other shaft section.

7. The improvement herein described comprising a car in combination with a side wing pivoted thereto, a secondary wing operatively connected to said side wing and 110 adapted to form an extension thereof, a shaft mounted on said car and comprising a plurality of sections, means for coupling and uncoupling said shaft sections to and from each other so that they may turn 115 simultaneously or independently of each other, means attached to one shaft section for imparting movement thereto and wing swinging and holding braces connecting said side wing to that shaft section to which said 120 means is attached and similar holding braces connecting the extension wing to said other shaft section.

8. The improvement herein described comprising a car, in combination with a side 125 wing, pivoted thereto, a secondary wing operatively connected to said side wing and adapted to form an extension thereof, a shaft journalled on the car and comprising a plurality of sections, means for coupling 130

105

1,550,785

5

and uncoupling said shaft sections, means so that when said shaft sections are uncoupled, said last mentioned brace bars may be fixed to one shaft section for rocking the same, foldable brace bars for connecting said last mentioned shaft section to said side ¹⁰ 5 wings and folding brace bars fixed at one end to the other shaft section and being detachably connected to the extension wing

In testimony whereof, I have hereunto set my hand, this 28 day of March, 1925.

JOHN F. CURTIS.
